UNITED STATES PATENT OFFICE.

HANNIBAL C. FORD, OF JAMAICA, NEW YORK.

TIME-OF-FLIGHT CLOCK.

1,355,829.

Specification of Letters Patent. Patented Oct. 19, 1920.

Application filed July 3, 1918. Serial No. 243,146.

To all whom it may concern:

Be it known that I, HANNIBAL C. FORD, a citizen of the United States, residing at Jamaica, in the borough of Queens, State of New York, have invented new and useful Improvements in Time-of-Flight Clocks, of which the following is a specification.

This invention relates to time of flight clocks or more particularly, to a clock for sounding an alarm to announce to a spotter or other observer, when he may expect a projectile which is fired at a known range or gun elevation to reach its target, so that he may concentrate his attention and determine whether the projectile hits the target, or the amount by which it misses it.

One object of the invention is to provide an instrument of this character which is of a simple construction and which is so constructed that direct readings of range or angular elevation of the gun may be utilized in setting the clock for a corresponding time of flight.

Another object of the invention is to provide an alarm controlling device which may be easily set to sound an alarm at the end of one or a plurality of time intervals, and which is automatically reset after the alarm has been actuated so that it will not again actuate the alarm.

Other objects of the invention will be apparent from the detailed description herein-after to follow when taken in conjunction with the accompanying drawings and will be particularly pointed out in the appended claims.

In the drawings:

Figure 1 shows a face view of a clock constructed in accordance with the principles of the invention;

Fig. 2 is a vertical section through Fig. 1 on the line 2-2, the alarm controlling disk being shown in full;

Fig. 3 is a plan of the clock removed from the casing, showing also the inside face of the cover plate;

Fig. 4 is a detail showing the re-setting cam for the pins and

Fig. 5 is a detail showing the bar for setting the pins.

The clock is inclosed within a water-tight casing consisting of the body part 1 and a cover plate 2, the cover plate being provided with a flange 3 which fits inside of the upper edge of the casing 1 and forms a tight joint at this point. Riveted to the bottom of the

casing 1, as at 4, is a gong 5 which is struck by a hammer 6 (see Fig. 3), when the alarm actuating device of the clock mechanism is put into action. The frame 7 of the clock mechanism is secured to the cover 2 by means of posts 8 and straps 9. This frame, as is the usual practice, consists of two plates 10 and 11 which are supported in spaced relation by posts 12. Mounted between these plates is a clock mechanism of a known type, comprising a barrel 13 which incloses the power spring (not shown). The barrel 13 carries a gear 14 which actuates a train of gears, the speed of rotation of the gears being controlled by a balance wheel 15, forming a part of the usual type of clock escapement.

This gear train actuates an alarm controlling disk 15, the gear ratios being such that this disk preferably makes one revolution a minute. The clock mechanism also actuates an alarm device which is controlled by a detent wheel 16 driven by the clock mechanism, which wheel is normally held against rotation by a detent 17 which is mounted upon a rocker shaft 18. This shaft carries the hammer 6 and also an alarm controlling lever 19. One tooth 17^a of the detent 17 normally prevents the detent wheel 16 from rotating when the lever 19 is held against movement. When, however, the controlling arm 19 is free to oscillate, the spring tension upon the detent wheel 16 is sufficient to throw the tooth 17^a out of engagement with the detent wheel 16 and permit its rotation. The teeth 17^a and 17^b will then alternately engage the teeth of the detent wheel and cause an oscillation of the controlling lever 19 and also of the hammer 6 which strikes the gong and sounds the alarm. These oscillations will continue until the lever 19 is again held stationary in a position in which the tooth 17^a engages one of the teeth of the detent wheel and prevents its further rotation. The controlling lever 19 is normally held against movement and in a position in which the tooth 17^a engages the ratchet wheel 16 by a pivoted lever 20, one end of which normally abuts against an upturned end 21 of the controlling lever 19, as disclosed in Fig. 3. When, however, this lever 20 is moved to its dotted line position, shown in this view, the end 21 of the controlling lever 19 will be free and hence the alarm will be actuated as described. The lever 20 is adapted to be displaced to its dotted line

position by the alarm controlling disk 15, which as before stated, is driven so that it makes one complete revolution in one minute. The disk 15 carries a plurality of pins 22 which fit loosely into holes in the disk adjacent to its periphery and are of a length greater than the thickness of the disk. The pins are held against displacement by a coiled spring 24 which fits in a groove in the peripheral face of the disk, the pins passing between the helical coils of the spring and the friction which is thus placed upon them being sufficient to prevent them from being inadvertently displaced and yet permit them to be positively moved in either direction and held in the position to which they are moved. In the embodiment shown, sixty pins are utilized and since the disk makes one revolution a minute, the space between adjacent pins equals the displacement of the disk in one second.

As will be clear from Fig. 3, the lever 20 is provided with a lug 26 which, when the pins are in their normal position, is disposed beneath the pins, the lever being under the tension of a spring 20^a which normally holds it against the end of a re-setting cam 27. If, however, one of the pins should be displaced to its lower position, as is shown in Fig. 4, or Fig. 5, this pin will then engage the lug 26 to throw the lever 20 against the spring 20^a, to its dotted line position and the alarm controlling lever 19 will then be free to oscillate and sound the alarm. After the pins have been displaced they are returned to their normal position by means of the re-setting cam 27 which is shown in Fig. 4, the cam having an inclined surface against which the pins ride as the disk actuates, which forces them upwardly to their normal position, where they remain until again positively displaced.

Referring now to the mechanism for displacing the pins, which permits the alarm to be sounded at any desired time interval corresponding to the time of flight of a projectile:—Mounted upon the cover 2 of the clock is a disk 30 which is provided with two scales, the scale 31 being a range scale calibrated in terms of the time of flights of a projectile. This disk 30 may also carry a scale 32 of gun elevation which is calibrated in terms of the corresponding time of flights of a projectile. In the embodiment shown the scales are calibrated for a 12" gun having an initial velocity of 2700 ft. sec. For calibrating these scales, since the disk 15 makes one revolution in a minute, the circumference of the dials is divided into 60 seconds and the values of range and gun elevation corresponding to time of flights and seconds, are laid out on the dial. The scales are read from a fixed pointer 33. The disk 30 rests upon an oiled

felt pad 34 (see Fig. 2) which makes the clock water-tight at this joint. The disk 30 also carries a knob or knurled bead 35 which is secured to a sleeve 36 by a set screw 36'. The sleeve 36 passes through an opening in the cover plate and carries a disk 37 mounted inside of the plate. Felt washers 38 are also provided between the head 35 and sleeve 36 to make the joint water-tight. The disk 37 is diametrically grooved or slotted as at 37^a and carries a pin setting bar 39 which is provided with a V-shaped setting end 40. This setting bar is carried by a plunger 41 within the sleeve 36 which extends above the knob 35 and is adapted to be manually pressed downwardly and to be returned to its normal position by a spring 42.

Referring to Fig. 5, the manner in which the setting bar 39 actuates the pins, is clearly disclosed. The knife edge of the V-shaped end 40 of the setting bar when the plunger 41 is pressed downwardly, is moved to the position shown in full lines in Fig. 5 and presses against one of the pins to also displace it. It is also evident from this figure that if the plunger 41 should be held in its displaced position, the inclined surface of the V-shaped end 40 will act as a cam, similar to the cam 27 and as the pins move into contact with it, they will be successively displaced.

The clock is controlled by a knob 50, marked the "Stop and run" knob. This knob is mounted upon a shaft 50' which passes through the cover plate and carries a finger 51 (see Fig. 3), which finger engages a spring 54 which normally acts as a brake upon the staff 15" of the balance wheel 15' to prevent its rotation but is moved out of engagement with the staff by the finger 51 when the knob 50 is turned to its "run" position.

The alarm device is controlled by a knob 55 marked "Alarm" and "Silent" which is clearly disclosed in Fig. 2, consisting of a shaft 56 which carries at its end a disk 57, having a flattened portion 58. As will be clear from Fig. 2, this disk is arranged in the path of the upturned end 21 of the alarm control lever 19. When the flattened portion 58 is adjacent to the end 21, sufficient space is provided to permit the lever 19 to oscillate freely. When, however, this knob 55 is turned so that the round edge of the disk is adjacent to the end 21, the oscillations of the alarm lever 19 are checked, which will prevent the alarm from being sounded, since the hammer 6 will be prevented from striking the gong.

If desired, an electrical alarm device may be utilized which comprises two spring contacts 60 and 61 which are normally out of engagement and are carried by an insulating block 62. These contacts are connected

5 by wires 63 and 64 to two terminals 65, which are provided with sockets to receive jacks or plugs, which would be connected by wires to any suitable annunciator, shown 5 diagrammatically in Fig. 1.

The clock is wound by a key 66 of the usual construction which key engages the square shaft 67 to wind the spring within the barrel 13.

- 10 To initially adjust the clock, the knob 35 is turned in a counterclockwise direction until the V-shaped end 40 of the setting bar 39 engages the pin 68, which is shown in full lines in Fig. 3 and in dotted lines in 15 Fig. 1. In this position of the setting bar 39 the knife edge 40 is directly over the pin 22^a (shown in Fig. 3). The set screw 36 is then loosened and the dial 30 is turned independently of the setting bar until the 20 zero graduation on the scale 31 coincides with the pointer 33. The set screw is again tightened and the dial and knob 35 will thereafter rotate with the setting bar 39.

The operation of the clock is as follows:—

- 25 The "Stop and run" knob 50 is turned to release the brake 54 and the clock train will then rotate the wheel 15 in a counterclockwise direction (see Fig. 3). While the pins 22 remain in their normal position, the lever 20 will not be actuated since these pins will 30 pass over the lug 26 without coming into contact therewith. Assuming now that a gun has been elevated for a range of 15,000 yds. and that it is desired to set the clock to 35 warn the observer of the impact of a shell fired from the gun:—The knob 35 is then turned in a clockwise direction (as in Fig. 1) until the graduation designated 15,000 1 yds. appears opposite the pointer 33. This 40 will also carry the setting bar 39 with it. The plunger 41 is then pressed downwardly when the gun is fired and the setting bar 40 will then engage one of the pins 22 and, as shown in Fig. 3, the pin which is displaced, being designated 22^b. The continued rotation of the disk will carry the displaced pin 22^b in a counterclockwise direction (as shown in Fig. 3) until it reaches the position designated by 22^a at which instant of time it 45 50 will actuate the lever 20 and release the alarm actuating lever 19 to sound an alarm, two or three seconds prior to the time of flight of a projectile whose range is 15,000 yds., which is 22 seconds. The spotter or observer will therefore be warned to look for and determine the point of impact of the projectile.

When it is desired to set the clock for a time of flight corresponding to any other 55 range the dial is turned until this range appears on the scales opposite the pointer 3 and the plunger 41 is again pressed downwardly when the gun is fired and a warning will then be sounded two or three seconds 60 prior to the impact of the shell.

The clock may also be used when the shots from the gun or guns follow each other in close succession, since by pressing the plunger 41 each time a shot or projectile is fired, the alarm will be actuated at the end of a time of flight corresponding to the different shots which although not distinguishable, will warn the spotter when each one of the projectiles is about to reach the target.

I claim:

1. In a time of flight clock, an alarm, a time controlled device for controlling the actuation of said alarm and means, including a scale calibrated in terms of range, for setting said time controlled device to actuate said alarm at the end of a time interval slightly less than the time of flight of a projectile from a gun elevated for a corresponding range.

2. In a time of flight clock, an alarm, a time controlled device for controlling the actuation of said alarm and means, including a scale calibrated in terms of gun elevation, for setting said time controlled device to actuate said alarm at the end of a time interval slightly less than the time of flight of a projectile from a gun elevated for a corresponding range.

3. In an alarm device, a time controlled rotary part, a plurality of displaceable members carried by said part, means for displacing said members at various positions in their rotary path, and an alarm device actuated by each of said members when displaced; and means for re-setting said members.

4. In an alarm device, a time controlled rotary part, a plurality of displaceable members carried by said part, means for selectively displacing said members, at various points in their rotary path, an alarm controlling device actuated by each of said members when displaced and a re-setting cam arranged in the path of said members for returning them to their normal positions.

5. In an alarm device, a time controlled rotary part, a plurality of displaceable members carried by said part, a rotary member having a displaceable part adapted to engage each one of said members to displace said member when said rotary part is displaced, and a re-setting cam for returning said members to their normal positions.

6. In an alarm device, a time controlled rotary part, a plurality of displaceable pins carried by said part, a friction grip for each of said pins for holding them either in their normal or displaced position, a rotary part for displacing said pins and an alarm controlled device for actuating said alarm engaged by each one of said pins when displaced and means for re-setting said pins.

7. In an alarm device, a time controlled rotary part, a plurality of displaceable pins carried by said part, a coiled spring engag-

- ing said pins and frictionally holding them in their normal or displaced positions, a rotary member carrying a bodily displaceable setting bar for displacing said pins, an alarm device actuated by said pins when displaced, and means for re-setting the pins after being displaced.
8. In a time of flight clock, a time controlled rotary part, a plurality of displaceable pins carried by said part, means for frictionally holding said pins in their normal or displaced positions, a rotary member carrying a time of flight scale calibrated in terms of gun elevation, a displaceable setting bar carried by said rotary member for displacing said pins, an alarm device actuated by a displaced pin, and means for re-setting the pins when displaced.
9. In a time of flight clock, a time controlled rotary part, a plurality of displaceable pins carried by said part, means for frictionally holding said pins in their normal or displaced positions, a rotary member carrying a time of flight scale calibrated in terms of gun elevation, a displaceable setting bar carried by said rotary member for displacing said pins, an alarm device actuated by a displaced pin, and means for re-setting the pins when displaced.

HANNIBAL C. FORD.
